INVENTOR

UNITED STATES PATENT OFFICE

97,007

DESIGN FOR A DRESS

Joseph Greenberg, New York, N. Y.

Application August 28, 1935, Serial No. 58,336

Term of patent 3½ years

To all whom it may concern:

Be it known that I, Joseph Greenberg, a citizen of the United States of America, residing in Manhattan, county of New York, and State of New York, have invented a new, original, and ornamental Design for a Dress, of which the following is a specification, reference being had to the accompanying drawing, forming part thereof, wherein,

The scroll and spiral-effect lines on the front and back of the waist and dolman sleeves represent embroidery.

I claim:

The ornamental design for a dress, substantially as shown, and described.

JOSEPH GREENBERG.
